CLAIM

The ornamental design for a lady shaver, as shown and described.

DESCRIPTION

FIG. 1 is a front, top and left perspective view of a lady shaver showing my new design;

FIG. 2 is a rear, bottom and right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion "9" shown in FIG. 1. In the drawings, the broken lines illustrate enlarged view indicators and form no part of the claimed design.
